UNITED STATES PATENT OFFICE.

JOSEPH R. BROWN, OF BRIDGEPORT, CONNECTICUT, ASSIGNOR TO THE AUTOMATIC FIRE EXTINGUISHER COMPANY, OF NEW YORK, N. Y.

AUTOMATIC FIRE-EXTINGUISHER.

SPECIFICATION forming part of Letters Patent No. 278,217, dated May 22, 1883.

Application filed February 21, 1883. (No model.)

To all whom it may concern:

Be it known that I, JOSEPH R. BROWN, of Bridgeport, in the county of Fairfield and State of Connecticut, have invented a certain new and useful Improvement in Automatic Fire-Extinguishers; and I hereby declare the following to be a full, clear, and exact description of the same, reference being had to the accompanying drawings, forming part of this specification.

This invention has reference to an improvement in what are known in the art of extinguishing fires automatically as "sensitive automatic fire-extinguishers," in which the solder is used to hold the extinguisher closed, and is placed away from the cooling effect of the water, so as to be readily acted upon by the heat from the fire.

The invention consists in the peculiar construction of the device, by which the release of the distributor will be more promptly effected, as will be more fully set forth hereinafter.

Figure 1 is a view of a sensitive automatic fire-extinguisher. Fig. 2 is an end view of the same. Fig. 3 is a sectional view of the same, showing the same in action. Fig. 4 is a sectional view of a sensitive automatic fire-extinguisher held against the internal pressure by two levers secured together by a fusible solder. Fig. 5 is an end view of the same. Fig. 6 is the distributor-disk.

In the drawings, *a* is the nipple by which the automatic fire-extinguisher is secured to the system of pipes.

b is an enlargement of the case.

c is a receptacle for the distributor.

d is a conical valve formed on the end of the stem *f*.

e is a soft-metal ring, which, with the valve *d*, forms a water-tight joint by which the entrance of the water to the distributor is prevented.

g is the distributor-disk.

h is a ring made of any suitable slow-conducting material—such as paper, felt, cork, or any composition suitable for this purpose—a shoulder being formed on the case to retain the same, as is shown in Figs. 3 and 4.

i are projections formed on the ring *j*, on which one end of the lever *k* is hinged or otherwise secured, the other end of the lever *k*

being secured by a solder fusible at a low temperature. The lever *k* bears against the distributor *g* and holds the same and the valve *d* in place until released by the action of heat, 55 when the whole device is forced by the pressure of the water to assume the position shown in Fig. 3.

Instead of one lever, as shown in Figs. 1 and 2, two levers may be hinged or hooked on 60 the projections *i* *i* and secured together by solder, and to somewhat relieve the direct strain on the solder one of the levers is provided with the pin *l*, which rests on the other lever. When the solder is sufficiently affected 65 by heat the two levers separate and the extinguisher is put instantly into operation.

As the water cannot enter the device, and the soldered joint is far removed from the water, this kind of automatic fire-extinguisher 70 is very sensitive to the action of heat, and is put into operation before a fire can get any headway, even with the most inflammable material.

m is a test-tap by which any water can be 75 drawn off that may have entered the device and the tightness of the valve ascertained.

I do not claim the use of the insulating-ring, broadly, as this is shown and described in another application filed at even date with this. 80

Having thus described my invention, I claim as new and desire to secure by Letters Patent—

1. In an automatic fire-extinguisher, the combination, with the valve *d*, ring *e*, constructed to exclude the water from the extinguisher, the stem *f*, the distributor *g*, and the case arranged to receive the same, of the ring *h* and the lever *k*, constructed to hold the distributor until the same is released by the action of heat, as described. 85

2. The combination, with an automatic fire-extinguisher, of a ring having a non or slow conducting material interposed between the ring and distributor, and levers constructed to hold the automatic fire-extinguisher and restrain its action until released by the action of heat, as described. 90

JOSEPH R. BROWN.
